US00D975740S

(12) **United States Design Patent** (10) Patent No.: **US D975,740 S**
(45) Date of Patent: **** Jan. 17, 2023**

(54) **ELECTRONIC DEVICE WITH GRAPHICAL USER INTERFACE**

(71) Applicant: **Apple Inc.**, Cupertino, CA (US)

(72) Inventors: **Eduardo Ahumada Apodaca**, Thousand Oaks, CA (US); **Vincenzo O. Giuliani**, Thousand Oaks, CA (US); **Harry Payne**, Culver City, CA (US)

(73) Assignee: **Apple Inc.**, Cupertino, CA (US)

(**) Term: **15 Years**

(21) Appl. No.: **29/786,148**

(22) Filed: **May 28, 2021**

Related U.S. Application Data

(63) Continuation of application No. 29/705,044, filed on Sep. 9, 2019, now Pat. No. Des. 921,029.

(51) **LOC (14) Cl.** **14-04**

(52) **U.S. Cl.**

USPC **D14/492**

(58) **Field of Classification Search**

USPC D14/485-495

CPC G06F 3/048-0497

(57)

CLAIM

The ornamental design for an electronic device with graphical user interface, as shown and described.

DESCRIPTION

The FIGURE is a front view of an electronic device with graphical user interface showing the claimed design. The broken lines in the FIGURE show an electronic device, and form no part of the claimed design.

1 Claim, 1 Drawing Sheet
